UNITED STATES PATENT OFFICE.

MAURICE S. ROSENFELD, OF NEW YORK, N. Y., ASSIGNOR, BY MESNE ASSIGNMENTS, TO JACOB SCHECHTER, OF NEW YORK, N. Y.

REVOLVING DOOR.

1,283,921.

Specification of Letters Patent.

Patented Nov. 5, 1918.

Application filed July 31, 1915, Serial No. 42,964. Renewed September 18, 1918. Serial No. 254,675.

To all whom it may concern:

Be it known that I, MAURICE S. ROSENFELD, a citizen of the United States, residing in the borough of the Bronx, county of Bronx, city and State of New York, have invented a new and useful Improvement in Revolving Doors, of which the following is a specification.

My invention relates to that class of door which is pivoted at the center, and revolves on such pivot instead of being hinged at one side of the door and capable of being swung back and forth on the hinges.

The objects of my invention are:

1. To produce a door of the revolving type wherein the number of parts will be materially reduced.

2. To provide means whereby the door will always swing to position across the vestibule.

3. To provide means whereby the doors may be operated as ordinary doors by swinging on pivots along their outer edges without the use of tools such as keys, bolts or the like; and

4. To provide means for locking the door in position across the door opening.

These and further objects will more fully appear in the following specification and accompanying drawings considered together or separately.

I have illustrated the preferred embodiment of my invention in the accompanying drawings in which,

Fig. 1 is a horizontal section of my improved revolving door and vestibule, taken on the line 1—1 of Fig. 2;

Fig. 2 is an elevation of a door and vestibule;

Fig. 3 is a horizontal section on the line 3—3 of Fig. 2;

Fig. 4 is a side elevation partly in section on the line 4—4 of Fig. 3;

Fig. 5 is a vertical section on the line 5—5 of Fig. 4;

Fig. 6 is a similar view showing the door locked against rotation on its central pivot when the valves are swung on their individual pivots;

Fig. 7 is a detail sectional view showing the door locked in position across the vestibule;

Fig. 8 is a section on the line 8—8 of Fig. 7;

Fig. 9 is a sectional view showing the lower pivot and lock.

Fig. 10 is a detail view showing a means for preventing backward movement of the door.

In all of the above views, like parts are designated by similar reference characters in all of the figures.

In the embodiment illustrated, I have shown my improved device in coöperative relation to a vestibule having side walls 1, 1 and entrance and exit openings 2, 2. Top beams 3 and 4 extend across the top of the vestibule which rests on a floor 5. A revolving frame composed of side members 6, 7, a top member 8, and a bottom member 9, is pivoted at 10 in the floor and by means of a tubular pivot 11, to the top beams 3 and 4. The pivot 11 is rigidly secured to the member 8, and rotates in the beams 3 and 4.

The side members 6 and 7 are each provided with wings 12 of a length sufficient to close the openings 2 when the revolving frame is in the position shown in dotted lines in Fig. 1.

Pivoted to the top and bottom members 8 and 9, and adjacent to the side members 6 is a valve 13 and a similar valve 14 is pivoted in the members 8 and 9 and adjacent to the side member 7.

Slidably mounted in the bore of the pivot 11 is a plunger 15 having a conical lower extremity 16. The conical lower extremity of the bolt is of reduced diameter, and a shoulder 17 is thus formed. Projecting from the reduced portion of the bolt is a pin 18. Carried at the upper end of the valve 13 at the point farthest removed from its pivot is a socket 19 provided with inclined sides 20, 20. Mounted in a socket in the free side of the valve 14 is a spring pressed plunger 21 which, when the valves are in alinement, will engage the socket 19 and lock the valves against relative movement.

The plunger 15 carries a pin 22 which projects through slots 23 in the pivot 11 and carries a clutch member 24 which coöperates with a clutch member 25 secured to the beam 3. The clutch members 24 and 25 are normally held out of engagement by gravity but if desired a spring may be employed for this purpose.

Carried in bearings 27 on the member 8 is a pin 28. A spring 29 holds the pin in

engagement with the bolt and when the latter is raised the pin engages under the shoulder 17 and holds the bolt up.

- Pivoted to the beam 4 at 31 is a lever having a long curved arm 32 and a short arm 33. The arm 33 is connected by means of a link 35 with a lever 36 pivoted at 37 to the beam 4. The lever 36 has an inclined extremity 38 and a shoulder 39. Attached to the lever 36 is a cord or chain 34 which passes around a pulley on the lever 32 and over a pulley 40 outside of the vestibule. A weight 41 is attached to the cord and serves to draw the levers toward each other.
- Rigidly secured to the pivot 11 is a pair of arms 42 which extend in the same longitudinal plane as the revolving frame. Each arm is provided with a roller 43 adapted to be engaged by the levers 32 and 36.
- The lower member 10 is provided with a pawl 44 which engages ratchet teeth in a base plate 45 and prevents backward movement of the revolving frame.

Carried by the free edge of the valve 13 is a lock 46, of well known construction, provided with three bolts 47, 48 and 49. The bolt 47 projects upward and is adapted to engage the pin 18. The bolt 48 projects downward and is adapted to engage a keeper in the plate 45. The bolt 49 projects laterally and is adapted to engage a keeper in wall of the vestibule. The bolt 49 is provided with a hinge 50 which is in line with the pivots of the valve in which the bolt is located.

The upper edges of the wings 12 and 13 are each provided with a flat plate 51, which will act as a roof when the door is in the position shown in dotted lines in Fig. 1.

The extremity of each lever 32 and 36 is provided with a roller 53 and 55 respectively. These rollers are supported on tracks 54 extending from the member 4 to the edges of the vestibule.

The operation is as follows:

With the revolving frame and valves in the position shown in Fig. 1, the frame may revolve in the direction of the arrow by applying pressure to the lower side of the valve 14 or the upper side of the valve 13. The pawl 44 will prevent movement in the opposite direction. When the revolving frame reaches the position shown in broken lines in Figs. 1 and 3, the roller 43 on the arm 42 will be about to leave the inclined portion 38 of the lever 36, and the lever 32 will, by reason of its connection to the lever 36 by the link 35, be swung to the position shown in dotted lines in Fig. 3. A slight forward movement of the revolving frame will cause the roller to pass from the part 38 and drop behind the shoulder 39. The weight 41 will return the levers 36 and 32 to their normal positions, and the engagement 65 of the lever 32 with the roller 43 nearest it

will swing the frame and valves over in the direction of the arrow. The weight 41 will hold the door as a whole in its closed position extending from side to side across the vestibule.

During the above described movement, the valve 13 is locked to the revolving frame by the engagement of the plunger 15 with a socket in the top of the valve, and the valve 14 is locked to the valve 13 by the engagement of the plunger 21 with the socket 19. 70 75

In case of emergency, such as a panic, when considerable pressure is applied to one or the other side of both valves near the adjacent edges thereof, the conical end of the plunger 15 will be forced from the conical socket in the valve 13 and the valves will be caused to turn on their pivots. The relative movement of the valves will cause the plunger 21 to be depressed, and the valves will be 80 free to swing to the positions shown in dotted lines in Fig. 1. When the plunger 15 is raised from its socket, the shoulder 17 will be brought above the pin 28, which will be forced inward by the spring 29 to engage 85 below the shoulder 17 and support the plunger out of contact with the valve 13. The raising of the plunger 15 will cause the clutch member 24 to engage the member 25 and lock the revolving frame against rotation. 90 When it is desired to again place the parts in position to act as a revolving door, the pin 28 is withdrawn from beneath the shoulder in the plunger. The plunger 15 will fall and its end will lie in the path of 95 the upper edge of the valve 13. On swinging the valve inward, the end of the plunger will be caused to engage the socket, and the valve will be locked. By swinging the valve 14 inward the plunger 21 will engage the 100 socket 19, thus locking the valves together. 105 The door may now be operated as first above described.

When it is desired to securely lock the door in the position shown in full lines in Fig. 1, a key is inserted in the lock 46 and turned. This movement will operate the bolts 47, 48 and 49, and the parts will be locked against movement.

In accordance with the provisions of the 110 patent statutes, I have described the principle of my invention together with the apparatus, which I now consider to represent the best embodiment thereof, but I desire to have it understood that the apparatus shown 115 is merely illustrative, and that the invention can be carried out in other ways without departing from the spirit of my invention.

Having now described my invention, what I claim as new and desire to secure by Letters Patent of the United States, is as follows:

1. A revolving door having a stationary frame, a revolving frame, a pivot carried by the latter and journaled in the former, a 130

plunger carried by the pivot, a valve pivoted in the revolving frame, a bolt carried by the valve, said bolt coöperating with the revolving frame to lock the valve to the frame, a 5 second valve pivoted in the revolving frame, a plunger carried by the second valve, said plunger coöperating with the first valve to lock the valves together, and means whereby the connection between the valves may 10 be broken by pressure on one valve.

2. A revolving door having a stationary frame, a revolving frame, a pivot carried by the latter and journaled in the former, a plunger carried by the pivot, a valve pivoted 15 in the revolving frame, a bolt carried by the valve, said bolt coöperating with the revolving frame to lock the valve to the frame, a second valve pivoted in the revolving frame, a plunger carried by the second valve, said plunger 20 coöperating with the first valve to lock the valves together, and means whereby the connection between the valves may be broken by pressure on one of the valves, and means for breaking the connection between the first 25 valve and the frame.

3. A revolving door having a stationary frame, a revolving frame, a pivot carried by the latter and journaled in the former, a plunger carried by the pivot, a valve pivoted in the revolving frame and engaged by 30 the plunger, a bolt carried by the valve, said bolt coöperating with the revolving frame to lock the valve to the frame, a second valve pivoted in the revolving frame, a plunger carried by the second valve, said plunger 35 coöperating with the first valve to lock the valves together, means whereby the connection between the valves may be broken by pressure on one of the valves, means for disengaging the plunger from the first mentioned valve, and for simultaneously locking the revolving frame to the stationary frame.

This specification signed and witnessed this first day of July, 1915.

MAURICE S. ROSENFELD.
